UNITED STATES PATENT OFFICE.

WILLIAM B. LONG AND CHARLES R. HUGHES, OF CHICAGO, ILLINOIS, ASSIGNEES TO UNION SPECIAL MACHINE COMPANY, OF CHICAGO, ILLINOIS, A CORPORATION OF ILLINOIS.

DEVICE FOR TURNING AND FOLDING TUBULAR FABRICS.

Application filed March 20, 1923. Serial No. 626,404.

This invention relates broadly to devices for turning and folding tubular fabrics, and in the particular embodiment of the invention illustrated and described, to a device for turning or reversing the upper end of a stocking so as to form the hem prior to stitching it.

Heretofore it has been proposed to turn or reverse a tubular fabric, particularly for forming the hem of a stocking, by means of a simple device comprising two upstanding wire arms spaced apart to permit the stocking to be placed between the arms and the open end to be slipped across the frames or fingers and turned backwardly over them. A portion of the exterior surface of these frames are suitably serrated to grip the fabric slightly so that when the extreme edge of the open end is folded back upon itself, to form the hem, the fabric is prevented from slipping on the frames. While this appliance is very simple, no provision is made to permit the facile release of the fabric from the serrated frames after the folding operation. This easy release is especially necessary where the frames are made of somewhat resilient wire stock.

The present invention has for one of its aims the provision of a simple device for folding the tubular fabric as hereinbefore set forth and for insuring the quick and ready release of the fabric from the supporting fingers or frames.

Still a further object of this invention is to provide a device which in addition to permitting the quick withdrawal of the fabric from the turning fingers or frames, also permits the easy positioning of the fabric upon the fingers.

Yet another feature of the invention resides in the simple and economical mode of providing the serrated faces constituting the fabric gripping portions of the supporting fingers or frames.

These and other objects will be apparent from a perusal of the following specification, in which—

Figure 1 is a side view of the appliance with the stocking in position thereon;

Fig. 2 is a detailed end view of the device;

Fig. 3 is a section on the line 3—3 of Fig. 1;

Fig. 4 is a section on the line 4—4 of Fig. 1, and

Fig. 5 is a detail of one of the supporting fingers.

Referring to the drawings in detail, the device comprises a support or bracket 1 of substantial T-shape, having suitable perforations 2 at its upper portion so that the bracket can be fastened to a desired support. The lower portion of the bracket is formed with an attached plate 3 preferably bolted thereto as at 4, which plate carries an extended arm 5. This arm is provided with a hollow bearing 6 in which is mounted the lower end 7 of the substantially semi-circular upstanding supporting finger or frame 8. To this end, the lower end is perforated as at 9 to receive the fastening screw 10.

The other supporting finger or frame 11 is mounted in spaced relation from the finger 8. These fingers are relatively movable. To this end, finger 11 is preferably carried on the end of a shiftable bar 12 which slides through a guideway 13 in the lower part of the bracket 1. The outer end of the bar 12 is detachably provided with a bearing member 14 which is preferably a counterpart of the member 6. This member 14 in like manner holds finger 11 in upstanding position. Suitable means is provided for shifting these fingers relatively. In the form illustrated, the extreme end of bar 12 is pivoted to a depending lever 15 as at 16, which lever is in turn pivoted as at 17 to one of the arms of the T-bracket 1. The lower end of lever 15 is suitably formed as at 18 so that it can be operated by the knee or body of the operator while his hands are engaged in positioning or withdrawing the stocking from the fingers 8 and 11. A coil spring 19 is connected to the bracket 1 and to lever 15 in such a manner as to normally maintain the fingers spaced apart the desired distance for properly folding and turning the stocking. An intermediate portion of bracket 1 is provided with a bored lug 20 in which is positioned a rod 21 as by thumb nut 22. This rod 21 is slotted or recessed as indicated in dotted lines at 23 in Fig. 1 of the drawings. This recess receives the lever 15. The length of the recess or slot 23 is slightly greater than the width of the lever, so that the lever can be moved back and forth in said recess or slot. The spring moves the

95

100

105

lever to the left as viewed in Fig. 1, until said lever strikes the end of the slot or recess 23, which end of the recess serves as a stop, or as means for limiting the movement of the lever. When the lever is moved in the opposite direction by the operator for moving the fingers toward each other, the lever will strike the outer end of the recess or slot 23, and this end of the lever serves as 10 a stop for limiting the movement of the lever stated.

The upper exterior fabric engaging faces of the fingers 8 and 11 are suitably serrated to provide fabric gripping means. A very 15 novel means is herein provided, consisting in a series of screw threads 24 suitably cut in the desired manner. These threads which are of the usual type are arranged with their apices pointing downwardly so as to 20 most effectively grip the fabric and prevent it sliding upwardly on the fingers during the turning and folding operation. The threads constitute a most important feature of our device, since they can be provided 25 economically. Preferably adjustable stops 23' are provided for each finger to limit the length of the fabric end before it is turned backwardly upon itself in the folding operation.

30 In the operation of the device, the lower end of lever 18 is moved to the right as viewed in Fig. 1 to bring the fingers slightly closer together and then the tubular fabric or stocking 27 shown in dotted lines is 35 positioned between the fingers; the open end 28 being slipped over the smooth top 25, 26 and pulled down on the fingers until it reaches the stops 23' as shown in Fig. 1. At this time the lever 18 is released so that 40 spring 19 forces the fingers apart, whereupon the serrations 24 grip effectively into the fabric. The lower end 28 is then drawn backwardly or upwardly into the dotted line position 29 to form the fold or hem. 45 During this reversing operation, the threads 24 hold the fabric from slipping on the fingers 8 and 11. After the above fold or hem is formed, the operator grasps the fabric at the folds and operates the lever 18 with 50 his knee to shift the fingers together slightly whereby to permit the easy release of the fabric.

It is obvious that minor changes in the 55 details of construction and the arrangement of the parts may be made without departing from the spirit of the invention as set forth in the appended claims.

Having thus described the invention, what we claim as new and desire to secure 60 by Letters-Patent, is—

1. A fabric turning and folding device comprising a support, a plurality of fabric engaging fingers mounted on said support, and constructed and arranged to grip said 65 fabric and to permit the fabric to be turned

thereon when so gripped, and means for shifting at least one of said fingers for releasing the grip of said fingers on said fabric.

2. A fabric turning and folding device 70 comprising a support, a plurality of fingers arranged thereon in spaced relation to permit the open end of a tubular fabric to be slipped thereover for turning and folding, and means for shifting one of said fingers 75 toward the other to facilitate the removal of said tubular fabric after turning.

3. A fabric turning and folding device comprising a support, a plurality of fingers arranged thereon in spaced relation to permit the open end of a tubular fabric to be slipped thereover for turning and folding, means on said fingers for gripping the fabric to prevent its inadvertent slipping therealong, and means for shifting said fingers 85 relatively to release said gripping.

4. A fabric turning and folding device comprising a support, an upstanding finger stationarily mounted thereon, a horizontal bar shiftably mounted in said support, a second upstanding finger mounted on said bar, means for maintaining said bar in a normally set position whereby said fingers are positioned a predetermined distance apart, and an operating member connected 95 to said bar and adapted on operation to shift the finger thereon toward said stationary finger.

5. A fabric turning and folding device comprising a support, a plurality of fingers arranged thereon in spaced relation to permit the open end of a tubular fabric to be slipped thereover for turning and folding, said fingers being suitably threaded for gripping the fabric to prevent its slipping during the turning operation, and means for shifting one of said fingers toward the other. 100

6. A fabric turning and folding device comprising a support, a plurality of fingers arranged thereon in spaced relation to permit the open end of a tubular fabric to be slipped thereover for turning and folding, said fingers being suitably threaded for gripping the fabric to prevent its slipping during the turning operation, means for shifting one of 105 said fingers toward the other, and means for adjusting said shifting means.

7. A fabric turning and folding device comprising a support, a stationary finger thereon, a shiftable finger thereon, a spring 110 adapted to normally space said fingers to permit a tubular fabric to be slipped thereover for turning and folding, an operating lever pivotally connected to said support and shiftable finger and operable to move said shiftable finger inwardly toward said stationary finger to permit the release of said fabric. 115

8. A fabric turning device comprising a 120 support, a fabric engaging and supporting 125

finger rigidly secured to said support, a bar movable endwise in said support, and a second fabric engaging finger carried by said bar, said fingers being substantially parallel and provided with serrated faces to resist the sliding movement of the turned portion of the garment during the reverse folding of the fabric, and manual means for moving said bar to release the grip of the fingers on the fabric.

9. A fabric turning device comprising a support, a fabric engaging and supporting finger rigidly secured to said support, a bar movable endwise in said support, a second fabric engaging finger carried by said bar, said fingers being substantially parallel and provided with serrated faces to resist the sliding movement of the turned portion of the garment during the reverse folding of the fabric, an arm projecting from said support, a lever pivoted to said arm and to said bar for shifting the bar endwise in said support, a spring connected to said lever for moving the lever in one direction, and a stop bar

having stops for limiting the movement of the lever.

10. A fabric turning device comprising a support, a fabric engaging and supporting finger rigidly secured to said support, a bar movable endwise in said support, a second fabric engaging finger carried by said bar, said fingers being substantially parallel and provided with serrated faces to resist the sliding movement of the turned portion of the garment during the reverse folding of the fabric, an arm projecting from said support, a lever pivoted to said arm and to said bar for shifting the bar endwise in said support, a spring connected to said lever for moving the lever in one direction, and an adjustable rod carried by the support and having means for limiting the movement of the lever through the action of the spring.

In testimony whereof, we affix our signatures.

WILLIAM B. LONG.
CHARLES R. HUGHES.
